(57) **CLAIM**

The ornamental design for a printer, as shown and described.

DESCRIPTION

FIG. 1 is a perspective view of a first embodiment of a printer, showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment of a printer, showing the new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The portions shown in light grey in FIGS. 1-7 depict environment and form no part of the claimed design.

The dot-dash broken lines depict the bounds of the claimed design, while all evenly spaced broken lines in FIGS. 8-14 are directed to environment. The broken lines form no part of the claimed design.

1 Claim, 14 Drawing Sheets
